UNITED STATES PATENT OFFICE.

GEORGE S. FLICKINGER, OF SAN DIEGO, CALIFORNIA.

LOCKING DEVICE.

1,124,882.

Specification of Letters Patent. Patented Jan. 12, 1915.

Application filed September 5, 1914. Serial No. 860,358.

To all whom it may concern:

Be it known that I, GEORGE S. FLICKINGER, a citizen of the United States, residing at San Diego, in the county of San Diego and State of California, have invented new and useful Improvements in Locking Devices, of which the following is a specification.

This invention relates to a locking device especially designed for locking a control lever of an automobile from motion, so as to prevent the automobile from being operated by an unauthorized person.

The primary object of the invention is to provide a locking device which is simple of construction, reliable and efficient in action, and which may be held engaged with the lever by any suitable type of lock, and is designed to retain the lock against loss or displacement when the device is not in use.

A further object of the invention is to provide a locking device possessing desirable advantages, as well as conveniences, in use.

The invention consists of the features of construction, combination and arrangement of parts herein fully described and claimed, reference being had to the accompanying drawing in which:

Figure 1 is a view showing the application of the invention for holding a control lever locked against movement. Fig. 2 is a horizontal section through the lever, looking down upon the locking device. Fig. 3 is a plan section through the arm of the locking device, and showing the hasp in open position. Fig. 4 is a side elevation showing the locking device folded up as when not in use. Fig. 5 is a front elevation of the same. Fig. 6 is a perspective view of the bracket *per se*.

Referring to the drawing, 1 designates an attaching bracket comprising a plate having openings 2 for the passage of fastening devices, whereby it may be secured to the riser of an automobile seat adjacent to the driver's position, as shown in Fig. 1. This bracket is provided with a pair of spaced forwardly projecting flanges or cheek plates 3 at opposite sides of the central portion thereof, and is formed at its upper end with apertured pivot ears 4 and at its lower end with a spring clasp comprising a pair of opposed spring jaws 5.

Carried by the bracket is a locking arm 6, which has one end fitted between the ears 4 and pivoted thereto by a pin or pintle 5, al-

lowing said locking arm to be swung inwardly and downwardly between the cheek plates 3 and jaws 5, or outwardly and upwardly to a horizontal locking position, as shown in Figs. 2 and 3. The intermediate portions of the plates 3 project outwardly beyond the plane of the locking arm when the latter is in folded position and are provided with receiving openings for a purpose hereinafter described.

The outer end of the locking arm is formed with a threaded socket 9 receiving a screw stem 10 which carries a substantially U-shaped shackle 11, the receiving space of which opens toward one side of the locking arm. The outer end of this shackle has hinged thereto a hasp 12 which is slotted at its free end to receive and engage a staple 13 carried by an extension 14 at the opposite end of the shackle, which staple is adapted to receive the bow of a suitable pad lock or analogous locking device 15.

The locking device is herein shown as applied to the riser of the driver's seat of an automobile employing a control lever 16, movable toward and from the seat. This control lever may be of a type which when moved toward the seat will apply the brake and throw off the high speed, and when moved forwardly or away from the seat will release a brake and throw on the high speed. When the lever is moved rearwardly to the first-named position the locking arm is thrown outwardly and upwardly the open side of the hasp is brought to a position to receive the lever, so that upon closing the hasp and engaging it with the staple the lever will be confined and held from movement, so that even by applying the lock 15 to the staple 13 and closing the bow of the lock the lever will be held locked to hold the brake applied and the transmission mechanism out of high speed adjustment. The vehicle thereupon may only be operated at low speed, if it can be driven at all against the action of the applied brake, so that it can not be run off or operated with any appreciable rate of speed by an unauthorized person.

It will, of course, be understood that the device may be employed to hold a lever which when set in a certain position will absolutely prevent the operation of the machine.

By means of the adjustable engagement of the stem 10 with the socket 9 the shackle may be adjusted in or out by action through

which the effective length of the locking arm is varied, so as to dispose the shackle at different distances from the seat for effective engagement with two levers which 5 when in applying position may vary to some extent in their distance from the seat. The construction of the device is such that when the hasp is turned outward, as shown in Fig. 3, it may be employed as a crank 10 to turn the shackle for adjustment, allowing greater ease of action and obviating the necessity of employing an auxiliary tube in the event that the screw stem is tight or rusted and hence difficult to turn. When 15 the device is not in use the locking arm may be swung downward between the cheek plates and held by the spring clasping jaw 5, and, if desired, the bow of the lock may be engaged either with the staple or with 20 the openings 8 in the cheek plate, by which the lock will be held against displacement. When engaged with the openings 8 the lock will also hold the locking device in folded position, as will be readily understood.

25 I claim:—

1. A locking device comprising a bracket plate having spaced cheek plates, an arm pivoted between the upper ends of said cheek plates to fold between and parallel 30 with said cheek plates, spring jaws at the opposite end of the bracket to engage and hold the arm in folded position, a shackle adjustably mounted upon the outer end of

the arm and providing a pivoted hasp, and a lock to engage the hasp. 35

2. A locking device comprising a bracket plate having spaced cheek plates, an arm pivoted between the upper ends of said cheek plates to fold between and parallel with said cheek plates, a screw stem adjustably mounted on the arm, spring jaws at the opposite end of the bracket to engage and hold the arm in folded position, a shackle carried by the stem and adjustable therewith, said shackle being provided with a pivoted hasp, and a lock to engage the hasp. 40 45

3. A locking device comprising a bracket plate having spaced cheek plates, provided with apertured portions, an arm pivoted between the upper ends of said cheek plates to fold between and parallel with said cheek plates, spring jaws at the opposite end of the bracket to engage and hold the arm in folded position, a shackle adjustably mounted upon the outer end of the arm and provided with a pivoted hasp, and a lock to engage the hasp, and adapted to be also engaged with the apertured portions of the cheek plates. 50 55 60

In testimony whereof I affix my signature in presence of two witnesses.

GEORGE S. FLICKINGER.
